CONTROL VALVE FOR COFFEE URNS OR THE LIKE

Walter B. Law and Warren B. Law, Dunellen, N. J.

Application March 25, 1947, Serial No. 137,882

Term of patent 14 years

(Cl. D91—1)

To all whom it may concern:

Be it known that we, Walter B. Law and Warren B. Law, citizens of the United States, residing at Dunellen, in the county of Middlesex and State of New Jersey, have invented a new, original, and ornamental Design for a Control Valve for Coffee Urns or the like, of which the following is a specification, reference being had to the accompanying drawing, forming part thereof.

Figure 1 is a view of one side of a control valve for coffee urns or the like, showing our new design;

Figure 2 is a view taken from the right of Figure 1;

Figure 3 is a view of the other side of said valve; and

Figure 4 is a top plan view thereof.

We claim:

The ornamental design for a control valve for coffee urns or the like, as shown.

WALTER B. LAW.
WARREN B. LAW.
